OBTURATOR FOR GUNS

William Summerbell, Washington, D. C., Louis J. Rhein, Aberdeen, Md., and Owen D. Hoopes, Arlington, Va.

Application April 11, 1945, Serial No. 537,816

1 Claim. (Cl. 89—26)

(Granted under the act of March 3, 1883, as amended April 30, 1928; 370 O. G. 757)

1

The invention described herein may be manufactured and used by or for the Government for governmental purposes, without the payment to us of any royalty thereon.

Our invention relates to obturators of the character adapted for use with a breech loading gun of the separate loading type wherein a primer cartridge is fired through a passage in the obturator to ignite and function the main propelling charge.

One of the problems long existing in firing guns of this character has been how to prevent injury to the spindle plug caused by the pressure of gases of the main propelling charge. The force of these gases, escaping rearwardly through the flash passage is very great and difficulty has been experienced in preventing these gases from escaping through the primer chamber, around the primer cartridge, thereby causing injury to the spindle plug necessitating frequent replacement, and also causing burning and warping of the primer cartridge case. It is, therefore, the principal object of our invention to provide an obturator for preventing the escape of such gases by providing sealing means for effectively confining the gases within the primer cartridge and the flash passage leading thereto, and preventing their rearward escape around the primer cartridge. This result is effected in part by crimping the lips of the primer cartridge upon insertion by forming an inwardly inclined, constricted portion in the inner end of the primer chamber. In addition means are provided for using the pressure resulting from the burning propellant gases for effectively pressing the side walls of the primer cartridge case tightly against the inner walls of said constricted portion, thus providing a substantial seal and thus preventing said propellant gases from escaping through the small space that would normally exist between the primer case and the walls of the primer chamber. Since the gases rush into the space inside the primer cartridge, the expansion of the gases therein will tend to expand the cartridge walls, thereby facilitating the sealing of the space between the primer cartridge and the walls of the primer chamber. Heretofore, it has been the practice to terminate the flash passage adjacent to the entrance to the primer chamber, and by this arrangement, the pressure of the gases was, partially at least, rearwardly against the lips of the primer cartridge and a portion of such gases frequently escaped between the walls of the chamber and the primer cartridge, resulting in the damage above referred to. By the use of our obturator the problem has

2

been solved, resulting in a considerable saving of time in changing spindle plugs and avoiding the consequent loss of fire power while the change was being made, as well as a saving of material.

With the foregoing and other objects in view, as will hereinafter more fully appear and as will be more particularly pointed out in the appended claim, reference is now made to the accompanying drawing forming a part of this application, in which:

Figure 1 is a horizontal, longitudinal sectional view, taken through a portion of an obturator, illustrating our improved mechanism.

Figure 2 is a detail perspective view of a baffle member employed in the invention, and

Figure 3 is an end view of Figure 2 taken along the lines 3—3.

Referring now to the drawing, a portion of an obturator is shown generally at 10. An obturator 20 spindle 12 is slidably mounted in a breechblock 12" and has its rearward end 14 provided with external threads 16 for threadably engaging matching threads 18 formed in a recess 20 at the forward end of a firing mechanism housing 22. The spindle 12 is held in the breechblock 12" by a helical spring 22' having one end seated on a washer 12' in the breechblock 12" and the other end bearing against a lock ring 18' keyed on the spindle 12 and abutting the firing mechanism housing 22. The housing 22 and the lock ring 18' are held against relative rotation by a pin 18" carried by the housing 22 and projected into the lock ring 18'.

The spindle 12 has a central longitudinal bore 35 or flash passageway 24 leading at its opposite or forward end, not shown, to the breech end of the barrel bore of the gun where is located the usual propelling charge. The housing 22 has a longitudinal bore 26 in which is located a spindle plug 28 the reduced rearward portion 39 of which extends into the reduced rearward portion 32 of bore 26 and the reduced threaded forward portion 34 of which threadably engages the inside of an enlarged annular threaded recess 36 in the rearward portion 14 of spindle 12.

The spindle plug 28 has a central longitudinal bore 38, the rearward portion 49 of which is of an inside diameter sufficient to receive a primer cartridge case 42. The primer 42 usually contains a black powder charge with a percussion sensitive material such as mercury fulminate, and a quantity of beeswax for closing the forward end of the primer. For purposes of clarity and because the individual designs of these primers may vary, the internal construction has not been il-

lustrated. The side walls 43 and 44 of the end 40 of the bore 38 are very slightly inwardly tapered from rear to front for the greater part of the length of the primer cartridge case 42, up to a location 46 from which location the said side walls converge slightly inwardly at a greater rate to the location 48 so that as the primer cartridge case is pressed into the bore 40, its forward lips 50 are crimped inwardly as indicated, thus making for a tighter fit of the lips of the cartridge case within the bore 40 particularly from location 46 to location 48. The degree of convergence of the bore 40 from location 46 to location 48 has been exaggerated in the drawing for purposes of clarity of illustration only.

The forward portion 52 of central bore 38 is enlarged and has tightly fitted therein a hollow cylindrical member or baffle 54 made of corrosion resisting steel or other suitable material. The baffle 54 has a central bore 56 equal in diameter to and axially aligned with bore 24 of spindle 12. An annular copper washer 58 having a central hole is located in the space at the inner or forward end of the recess 36 as shown. Members 28 and 54 have at their forward ends, projecting circular portion 60 and 62 respectively, which are V-shaped in cross section. The inner surface of recess 36 has a circular projection 64 also V-shaped in cross section. These projections 60, 62 and 64 are pressed into copper washer 58 as the surrounding members are drawn together, thus enhancing the sealing effect of the washer 58 against escape of gases around it.

As shown in the drawing, the rearward end surface of baffle 54 extends radially inward from locations 66 to 68 and then inclines convergently inwardly toward location 70 whence it extends radially inward to the inner surface of bore 56 at location 72. It will be noted, as illustrated, that the lips 50 of primer cartridge case 42 do not touch baffle 54 at any point, although the primer cartridge case 42 is fully inserted into bore 40 as far as it is supposed to go. It will also be noted, as illustrated, that the rearwardly extending lip 74 of baffle 54, that is, the portion extending rearwardly of location 68 extends rearwardly by a distance sufficient to extend slightly inside the lips 50 of primer cartridge case 42 but not touching them.

By means of the construction illustrated and described, it has been found that the gases from the burning propellant, which rush rearwardly through passageway 24 and bore 56 do not escape around the outer surfaces of primer cartridge case 42, but are effectively sealed in against escape by this route.

Thus the gases rush rearwardly into the interior of the primer cartridge case 42 and, due to their great pressure they serve to expand the primer outwardly against the walls of bore 40 sealing the gases from escaping between the outer surface of the primer and the inner surface of bore 40. Then the rearwardly rushing gases change direction and reach the region between the outer sloping surface of the annular lip 74 of baffle 54 and the extreme forward end of lips 50 of the primer cartridge case 42, but by this time the primer walls have been expanded so tightly

against bore 40 that the gases cannot escape around the primer.

In prior obturators, not using this invention, there has been considerable burning and warping of the primer cartridge case outer surface and the inner wall of the bore 40. However, by use of the invention described herein, this difficulty has been overcome.

The primer cartridge case 42 is firmly held in place with its sides within the bore 40 as indicated, and its rim 76 resting against and within a recess 78 formed in the rearward end of a hollow cylindrical extractor 79 the sides 80 of which are slidably located in the space between the inner surface of bore 32 and the outer surface of rearward portion 38 of spindle plug 28. Any suitable means, such as a movable block 82 which is diminutive as compared to the breech block of the gun is used for pressing primer cartridge case 42 into bore 40 and holding it there while the gun is fired. The construction of the extractor 79 and breech block 82 is the subject of and is more fully described and illustrated in our copending patent application, Serial No. 604,286, filed July 10, 1945, entitled Firing mechanism.

While the invention has been described in specific terms, it is to be understood that various changes may be made in the shape, size, materials and arrangement without departing from the spirit and scope of the invention.

We claim:

An obturator for use in breech loading guns of the separate loading type, comprising an obturator spindle having a flash passage therethrough, a plug in the rear end of said spindle provided with a primer cartridge chamber having a tapered front end to contact the front end of a primer cartridge when said cartridge is fully inserted in said chamber, means carried by the plug forward of said chamber and protruding therein to direct the gases from the propellant charge of the gun to expand the forward end of a cartridge case into gas sealing contact with the tapered portion of the chamber to block the passage of the gas from between the outer surface of the primer case and the inner wall of said chamber, said means comprising a baffle member in the plug having a flash passage therethrough communicating with the primer cartridge chamber and having an annular lip on its rear end surrounding the passage through said baffle member extending into the open end of the cartridge case and constructed and arranged to direct the gases into the cartridge case chamber.
